UNITED STATES PATENT OFFICE.

BEATRICE ELIZABETH MARIA BARTON, OF BIRMINGHAM, ENGLAND.

DESIGN FOR A MASONIC PENDANT.

58,304.

Specification for Design.

Patented July 12, 1921.

Application filed January 13, 1921. Serial No. 437,102. Term of patent 3½ years.

To all whom it may concern:

Be it known that I, BEATRICE ELIZABETH MARIA BARTON, subject of the King of Great Britain, residing at 5 Warstone Parade East, Birmingham, in the county of Warwick, England, have invented a new, original, and ornamental Design for a Masonic Pendant, of which the following is a specification, reference being had to the accompanying drawing, forming a part thereof.

The figure is an elevation of a Masonic pendant in an open position, showing my new design.

I claim:—

The ornamental design for a Masonic pendant, as shown.

BEATRICE ELIZABETH MARIA BARTON.
